UNITED STATES PATENT OFFICE.

WALTER SCOTT, OF PLAINFIELD, NEW JERSEY.

STOP-CYLINDER PRINTING-MACHINE.

SPECIFICATION forming part of Letters Patent No. 295,057, dated March 11, 1884.

Application filed March 29, 1883. (No model.)

To all whom it may concern:

Be it known that I, WALTER SCOTT, a subject of the Queen of Great Britain, residing at Plainfield, in the county of Union and State of New Jersey, have invented a certain new and useful Improvement in Stop-Cylinder Printing-Presses, of which the following is a specification.

My invention relates to that class of printing-machines which are known as "stop-cylinder presses," and the object of my invention is to provide a mechanism for starting, stopping, and holding the impression-cylinder in position while the form-bed is reciprocated one or more times for each impression taken. This object I accomplish by the devices illustrated in the accompanying drawings, in which—

Figure 1 is a side view of a portion of a press with my improved starting, stopping, and holding mechanism applied thereto. Fig. 2 is a plan view of the same. Figs. 3 and 5 are side views of modified forms of construction, and Figs. 4 and 6 are plan views of the same.

Similar letters refer to similar parts throughout the several views.

Upon the crank-shaft A, I loosely mount a box, a, which carries a sliding bar, B. In one end of this sliding bar B there is a slot, b, which engages with a pin, c, projecting from a toothed lever, C. This lever C is pivoted to the side frame of the press at d, and its upper end engages with the teeth of a segment, D, which is bolted to the end of the impression-cylinder E. This cylinder is mounted in the usual manner, and revolves once for every revolution of the crank-shaft, unless it is thrown out of gear in order to double-roll the form or stone.

Resting on the sliding bar B is a hook, F, one end of which is pivoted to the frame of the press, while the other end is arranged to engage with a pin, e, projecting from the lever C. The sliding bar B is operated by two cams, G and H, said cams being attached to the crank-shaft A, one on either side of the sliding bar. Two friction-rollers, g and h, are carried by the bar B, and ride on the faces of the cams G and H, by which arrangement a reciprocating motion is imparted to the bar B

when the crank-shaft A is revolved. A counter-balance, I, is fixed to the projecting end of the bar B, the object of which is to decrease the strain on the mechanism employed for lifting the bar. A gear-wheel, J, is secured to the crank-shaft A, and meshes with another gear-wheel, K, which is mounted on a short shaft, L, said gear-wheel K being twice the diameter of the gear J. A cam, i, is secured to the gear K by means of a set-screw, so that it can be disconnected when desired. A lever, M, pivoted by a shaft, j, sustained by the frame-work of the press, carries a friction-roller, k, which bears against the under side 65 of the bar B. Secured to one side of the lower arm of this lever M is a connecting-rod, l, one end of which is forked to straddle the shaft L. This rod l carries a friction-roller, m, which bears against the cam i.

When it is desired to pass the form or stone beneath the inking-rollers twice for each impression taken, the cam i is secured to the gear K, and as such gear is twice the diameter of the gear J, with which it meshes, it follows 75 that the cam will make but one revolution to two revolutions of the crank-shaft. It may be here remarked that in presses of this character the bed is geared to make one complete excursion to each revolution of the crank-shaft. As the cam i strikes against the friction-roller m, it forces said roller outward and away from the shaft L, by which movement the lower end of the lever M, through the medium of the connecting-rod l, is in turn 80 forced downward, while the upper end of such lever, which carries the roller k, is raised, and by it the bar B and the hook F. This raising of the bar B breaks the connection between it and the lever C, and leaves the bar free to 85 slide without moving the lever C, said lever being then held in position by means of the hook F, which has been thrown into engagement with the pin e. It will thus be seen that at every second revolution of the crank-shaft 90 the bar B will be thrown out of connection with the lever C, and consequently that the impression-cylinder will remain at rest.

On the side of the lower arm of the lever M opposite to that to which the rod l is secured there is pivoted a second rod, n, the other end of which is secured to an arm, o, of a

rock-shaft, *p*, which reaches across the press, and on its further end carries another arm, *q*, which engages with a rod projecting downward from a foot-treadle. It will be seen that by pressing the foot-treadle down the rock-shaft *p* will be partially rotated and the lever *M* raised, thus breaking the connection between the rod *B* and the lever *C* and throwing the hook *F* into engagement with the pin *e*. This means of holding the impression-cylinder at rest is resorted to when it is desired to reciprocate the form-bed an indefinite number of times for each impression taken; but to prevent this operation while the cylinder is in motion I employ the following-described combination of devices: A bell-crank lever, *N*, is mounted on a short shaft, *v*, and connected at its upper end to a rod, *t*, which reaches to and straddles the shaft *L*, and carries a friction-roller, *u*, which bears against two cams, *r r'*, which are secured to the shaft *L*. At the end of the lower arm of this lever *N* there is a catch, *w*, which engages with a slot, *x*, in the arm *o* of the rock-shaft *p*, thus preventing the shaft from being turned, except at such time as it is proper to trip the parts. As the cams *r r'* are mounted on opposite sides of the shaft *L*, it will be seen that at each revolution of the crank-shaft *A* the rod *t* will be forced away from the shaft *L*, thereby withdrawing the catch *w* from the slot *x*, so that the operator can throw the bar *B* up and out of engagement with the lever *C*. Another lever, *O*, which serves to hold the lifting-lever *M* in position after it has been raised and prevent its return until the proper time, is secured to the side frame of the press at *x'*. To the lower arm of this lever there is attached a rod, *y*, which reaches to the shaft *L*, and is there operated, through the medium of a friction-roller, *z z'*, by the cams *z z'*. The upper end of this lever *O* is hooked and engages with a pin or lug, *a'*, which projects from the lever *M*, by which arrangement the lever *M* is held up until the arrival of the proper time to lower the bar *B*. The lever *M* is kept from falling toward the crank-shaft by the pin *e'*, which is fixed to the shaft *j*, and rides in a slot formed in the hub of the lever, as shown by dotted lines in Fig. 1.

In Figs. 3 and 4 I have illustrated a modification of my improved mechanism for controlling the action of the impression-cylinder, wherein the hook *F* is pivoted to the frame of the press below the bar *B*. In this case a short arm projecting from the hook bears against a rib, *b'*, which is formed on the side of the bar *B*, and as the bar is raised so as to be clear of the lever *C*, the hook will drop onto the pin *e* and hold the lever in position. I have also shown in Figs. 3 and 4 another form of lifting device, which consists of a transverse lever, *h*, one end of which passes beneath a lifting-rod, *g*, while the other end reaches to the actuating mechanism, which is located at the opposite side of the press.

The lifting-rod *g* reaches up to and is pivoted to a double-faced cam, *f'*, said cam being in turn pivoted to the frame of the press at *k'*. This cam is so formed that when the bar *B* is raised in order to pass the form beneath the inking-rollers more than once for each impression taken, the cam is turned so that its surface *i* will bear against the bar *B*; consequently the bar *B* will have a flat, smooth surface to ride upon.

In Figs. 5 and 6 I illustrate still another way of arranging the bar and hook. In this case but one pin is carried by the lever *C*, the hook *F* being, as usual, pivoted to the frame, but having a pin, *e'*, which rides in the slot *d'*, formed in the bar *B*, so that when the bar *B* is raised and thrown out of connection with the lever *C* the hook *F* will be raised and brought into engagement with the pin which projects from the lever *C*.

It will be understood that, while I have described a specific mechanism for raising the sliding bar *B*, there are other mechanisms—such as the one shown in my application No. 79,876, filed December 21, 1882—which will accomplish the same result.

Having thus fully described my invention, what I claim as new, and desire to secure by Letters Patent, is—

1. The combination, with the crank-shaft and sliding bar, of an impression-cylinder having a toothed segment, a toothed lever arranged to engage with said segment, a lever, as *M*, for lifting said sliding bar, a rock-shaft, as *p*, having connections whereby it is adapted to be actuated by the operator, means for connecting the said rock-shaft with the lever *M*, and mechanism for preventing the rotation of the said rock-shaft when the impression-cylinder is in motion, all substantially as set forth.

2. The combination, with the lever *C*, sliding bar *B*, and mechanism, substantially as described, for reciprocating said bar, of gear-wheels, as *J K*, a cam, as *i*, a rod, as *l*, a lever, as *M*, and tripping mechanism, substantially as described, adapted to be actuated by the operator for raising the upper end of the lever *M*, and thereby breaking the connection between the bar *B* and lever *C*, and keeping the said bar and lever disconnected at pleasure, as set forth.

3. The combination, with the bar *B*, of a lever, as *M*, connecting-rod, as *n*, arm, as *o*, and rock-shaft, as *p*, substantially as described.

4. The combination, with the bar *B*, of a lever, as *M*, connecting-rod, as *n*, arm, as *o*, rock-shaft, as *p*, and a mechanism, substantially as described, for preventing the movement of the parts, except when the impression-cylinder is at rest.

5. The combination, with the bar *B*, of the lever *M* and its operating mechanism, and mechanism, substantially as described, adapted to be actuated by the operator, for elevat-

ing the upper end of said lever and keeping the same elevated at pleasure, all substantially as set forth.

6. The combination, with the bar B and lever M, of a lever, as o, a rod, as y, and actuating-cams, as z z', substantially as described.

7. The combination, with the bar B, of a lever, as M, connecting-rod, as n, arm, as o,

rock-shaft, as p, a second lever, as N, provided with a catch, as w, a connecting-rod, as t, and actuating-cams, as r r', all arranged and combined as and for the purpose specified.

WALTER SCOTT.
